CLAIM

The ornamental design for a broken screw extractor, as shown and described.

DESCRIPTION

FIG. 1 is a perspective view of a broken screw extractor in accordance with the new design;

FIG. 2 is a front view of the broken screw extractor of FIG. 1;

FIG. 3 is a rear view of the broken screw extractor of FIG. 1;

FIG. 4 is a left side view of the broken screw extractor of FIG. 1;

FIG. 5 is a right side view of the broken screw extractor of FIG. 1;

FIG. 6 is a top view of the broken screw extractor of FIG. 1; and,

FIG. 7 is a bottom view of the broken screw extractor of FIG. 1.

In the drawings, the broken lines illustrate portions of the broken screw extractor that form no part of the claimed design.
